(57) **CLAIM**

The ornamental design for an artificial crayfish plastic bait, as shown and described.

DESCRIPTION

FIG. 1 is a perspective view of an artificial crayfish plastic bait showing my new design;

FIG. 2 is a top plan view thereof;

FIG. 3 is a left side elevational view thereof, the opposite side being a mirror image;

FIG. 4 is a bottom plan view thereof;

FIG. 5 is a front elevational view thereof; and,

FIG. 6 is a rear elevational view thereof.

The broken lines in the drawing represent environmental subject matter that forms no part of the claimed design.
